UNITED STATES PATENT OFFICE.

SIDNEY A. ANDERSON, OF JERSEY CITY, NEW JERSEY.

SYNCHRONIZING DEVICE FOR ADDRESSING AND STAMP-AFFIXING MACHINES.

1,091,470.

Specification of Letters Patent. Patented Mar. 31, 1914.

Application filed April 5, 1913. Serial No. 759,052.

To all whom it may concern:

Be it known that I, SIDNEY A. ANDERSON, a citizen of the United States, and a resident of Jersey City, in the county of Hudson and 5 State of New Jersey, have invented a new and useful Synchronizing Device for Addressing and Stamp-Affixing Machines, of which the following is a specification.

My invention relates to a device which can 10 be attached to an addressing machine to operate a stamp-affixing machine, so that an envelop may be stamped simultaneously with the putting on of the address.

In the accompanying drawings I have 15 shown a multipost stamp-affixing machine in outline and so much of an Elliott addressing machine as is necessary to illustrate my invention.

Figure 1 is a front elevation; Fig. 2 is a 20 plan; Fig. 3 is a right sectional elevation on the line 3—3 and Fig. 4 is an enlarged cross section on the line 4—4.

In the addressing machine there is a base or table 1 on which is mounted a horizontal 25 rocking member 2, to which is attached a depending arm 3, by means of which a rocking movement is obtained. An ink roll 4 is mounted between the forward ends of a pair of arms 5 which extend forward from the rocker 30 2. The stencils 6 are carried through the machine in a pair of guide rails 7. The position of an envelop when being addressed is indicated by the dotted line 8 in Fig. 2. When one of the stencils 6 is directly under 35 the roll 4 the arm 3 is moved to the position indicated by dotted line in Fig. 3, causing the roll to descend and to print the address on the envelop through the stencil.

My device comprises an L-shaped upright 40 or standard 9, secured by a bolt 10 to the base 1. On this upright is mounted a slide 11 which is secured by clips 12. On the front of the slide there is a bracket 13 which has a horizontal portion 14, to the top side of 45 which is secured an arm 15 which has a slot 16—a knurled clamp screw 17 passing through the slot to hold the arm firmly. To the rear end of the arm 15 I secure, by means of a nut 18, the stem 19 of the stamp-affixing machine 20. The detailed construction 50 of the stamp-affixing device is not shown; suffice it to say that it operates in a manner similar to an ordinary numbering machine. On depressing the stem, the body of the machine is seated on the envelop and a further 55 downward movement of the stem causes a

stamp to be cut off and affixed to the envelop. A reservoir 21 has been added so that a supply of water can be put in without detaching the machine from its holding arm 15. 60

The slide 11 is reciprocated by an arm 22, the rear end of which is secured by a pair of clamping yokes 23 to the rocker 2. Attachment is made to the slide 11 near the front end of the arm 22 by means of a spring 24. 65 The slide 11 has a pin 25 which is normally held against the upper edge of the arm 22 by the spring 24. A safety pin 26 is placed in the lower end of the slide 11 a little distance from the lower edge of the arm 22, 70 to prevent unduly stretching the spring.

It is evident from the foregoing construction that as the rocker 2 is rocked to the position shown by dotted lines in Fig. 3, the slide 11 will be moved downward and that 75 the stamp-affixing machine 20 will be seated on the bed 1, and that, if an envelop be placed in position on the bed a stamp will be affixed thereon. The spring 24 is to make provision for thick or thin envelops and for 80 a pile of envelops and the movement is so arranged that the arm 22 will leave the pin 25 slightly on every downward stroke, thereby giving a slight dwell to the stamp-affixing machine. The slot 16 in the arm 15 permits 85 of the stamp-affixing machine being adjusted over a limited area so as to accommodate different sizes of envelops.

No drilling or machine work is necessary in attaching my device to the addressing 90 machine in the first place—the hole for the screw 10 being already in the machine. It is easily detached, by loosening either of the knurled screws or nuts, or by removing the supporting standard, in case it is desired 95 to use the addressing machine without affixing stamps. By using my device the time of an operator to put on the stamps is entirely saved.

Having now described my invention, what 100 I claim and desire to secure by Letters Patent is:

1. In a mechanism for synchronizing an addressing machine with a stamp-affixing device, the combination of the following 105 elements: a standard secured to the bed of said addressing machine; a slide adapted to reciprocate on said standard; means for securing said stamp-affixing device to said slide and means for simultaneously operating 110 said addressing machine and reciprocating said slide.

2. An addressing machine having an inking device, in combination with a stamp-affixing device; means for securing said stamp-affixing device to said addressing machine, which means holds said device to and permits of a reciprocating movement to and from said addressing machine; and means for simultaneously operating said inking and stamp-affixing devices.
3. In a synchronizing mechanism for an addressing machine and a stamp-affixing device, the combination of the following elements: a standard secured to said addressing machine; a slide adapted to reciprocate on said standard; an arm secured to said slide and adapted to support said stamp-affixing device; a movable arm adapted to reciprocate said slide—said arm being yieldingly attached to said slide.
4. In a synchronizing mechanism for an addressing machine and a stamp-affixing device, the combination of the following elements: a standard secured to said addressing machine; a slide adapted to reciprocate on said standard; an arm secured to said
- slide and adapted to hold said stamp-affixing device—said arm being adjustably secured to said slide, whereby said stamp-affixing device may be universally adjusted in a horizontal plane; and means for reciprocating said slide to operate said stamp-affixing device simultaneously with the operation of said addressing machine.
5. An addressing machine having an inking device and a member adapted to rock on a horizontal axis to operate said inking device; in combination with a standard secured to said addressing machine; a slide mounted on and adapted to reciprocate on said standard; a stamp-affixing device; connections between said slide and said stamp-affixing device; an arm clamped to said rocking member and a spring connecting the outer or free end of said arm to said slide.

In testimony whereof I affix my signature in presence of two witnesses.

SIDNEY A. ANDERSON.
